UNITED STATES PATENT OFFICE.

JOHN M. CASE, OF COLUMBUS, OHIO, ASSIGNOR TO THE CASE MANUFACTURING COMPANY, OF SAME PLACE.

GRADUAL-REDUCTION MACHINE FOR MANUFACTURING FLOUR.

SPECIFICATION forming part of Letters Patent No. 297,760, dated April 29, 1884.

Application filed May 31, 1883. (No model.)

To all whom it may concern:

Be it known that I, JOHN M. CASE, a citizen of the United States, residing at Columbus, in the county of Franklin and State of Ohio, have 5 invented certain new and useful Improvements in Gradual-Reduction Machines for Manufacturing Flour, of which the following is a specification.

My invention relates to an improved roller-mill for gradual-reduction milling.

It has for its object the production of a simple, cheap, and efficient roller-mill which shall perform the several reductions necessary in gradual-reduction milling, all combined in one 15 compact and simple machine, thus enabling the miller of small means to compete with roller-mills of the most improved construction. I construct my improved roller-mill with two parallel rolls which are corrugated in different 20 degrees of fineness, the coarser corrugations receiving the grain for the first reduction, and the finer corrugations for the subsequent reductions. In my improved mill I use a frame having adjustments for opening and closing 25 the rolls, which I have fully described in another application of even date herewith, Serial No. 96,699, for Letters Patent for improvements in roller-mills. These adjustments are not represented in this application.

30 In the accompanying drawings, Figure 1 is a longitudinal section of the machine on the line 1 1, Fig. 3. Fig. 2 is a longitudinal section of the same on the line 2 2, Fig. 3. Fig. 3 is a transverse section thereof on the line 3 35 3, Figs. 2 and 4. Fig. 4 is a detached perspective view of the delivery-hoppers and pneumatic elevating-pipes hereinafter described.

My improved rolls are constructed of two 40 sectional rollers running on horizontal shafts converging slightly from one end to the other. The ends 1 1 of these rolls for the first break are corrugated very coarsely, ordinarily in a straight line with the roll. In the third, fourth, fifth, and sixth sections of the rolls the corrugations are preferably in spiral form. The 45 rolls are placed wider apart at one end than at the other, and the sections gradually approach each other until close enough for the final cleaning of the bran or finishing of the

reductions where they come very close to each other.

In my improved mill the stock is first fed in at the end having the coarse corrugations through the pipe a. It passes between the rolls at 1, and by the operation of the revolving brush 7 (shown in Figs. 2 and 3) it is brushed around in the screen 8, and the middlings made are sifted through into the hopper 9 below and taken off by the conveyer 10, while the broken wheat is brushed over the 60 edge of the screen into the first elevating-spout 11.

In this construction of mill I use a system of air-elevators similar to that which I have described in other applications of even date 65 herewith, Serial Nos. 96,702 and 96,703, for Letters Patent on improved process in milling and improved bolting apparatus. The material passing through the coarse corrugations after being sifted is elevated by the air-current 70 in the pipe 11 and discharged into one of a series of settling air-chambers, 17, immediately above the rolls. The material from the first break is, by the action of a corrugated feed-shaft, 18, and valve 19, fed down into 75 the second section of the corrugated rolls, and from thence is again brushed over the wire screen below and discharged into the next air-tube 12, and by this elevated into the next section of the settling-chamber 17 above, and 80 so on. This treatment is constantly repeated until the final operation, when the bran is passed off and treated on special bran-rolls or sent to the "finished feed," as it may be thought proper. I use a series of valves, b, 85 one over each of the several settling-chambers, to regulate the strength of air-current necessary to produce the elevation of the material as it passes into the several elevating-tubes. The object of the flexible feed-valve 19 90 is to prevent air rushing up into the settling air-chamber, and at the same time permit of the stock being fed down by the corrugated roll 18 from the settling-hoppers onto the sections of the rolls below.

In practical operation I adjust my improved rolls in such a manner that the end 1 simply splits the grain in halves. At the next oper-
